UNITED STATES PATENT OFFICE.

JOSÉ VARGAS GUERRA, OF SANTIAGO DE CUBA, CUBA.

TELEGRAPH INSTRUMENT.

1,348,717.

Specification of Letters Patent.

Patented Aug. 3, 1920.

Application filed March 31, 1920. Serial No. 370,287.

To all whom it may concern:

Be it known that I, JOSÉ V. GUERRA, a citizen of Cuba, and a resident of Santiago de Cuba, in the Province of Oriente and 5 Republic of Cuba, have invented a new and Improved Telegraph Instrument, of which the following is a full, clear, and exact description.

This invention relates to improvements in 10 telegraph instruments, an object of the invention being to provide an improved mounting for the parts of the instrument so that the magnets can be adjusted to vary the gap between the magnet cores and the 15 armature operated thereby.

A further object is to provide improved means for controlling and adjusting the elastic support of the armature carrying lever and permit an adjustment of the 20 magnets relative to the armature to produce the best results.

A further object is to provide an instrument of the character stated embodying in 25 its construction various novel elements co-operating in the production of an instrument which is extremely sensitive and adjustable to suit all conditions.

With these and other objects in view the invention consists in certain novel features 30 of construction, and combinations and arrangements of parts as will be more fully hereinafter described and pointed out in the claims.

In the accompanying drawings—

35 Figure 1 is a top plan view;

Fig. 2 is a view in side elevation; and

Fig. 3 is a view in vertical transverse section on the line 3—3 of Fig. 2.

1 represents the base of my improved instrument which is preferably of wood or other similar material, and on which a metal platform 2 is secured by screws 3 which project through the base and into feet 4 on the plate 2 so that the latter is 40 supported at an elevation above the base. A pair of vertical guide pins 5, 5, are secured on the plate 2 and operate as guides for a bridge 6, the latter being perforated to receive the pins 5, and coiled springs 7 are located around the pins 5 between the bridge 6 and the plate 2 tending to elevate the bridge. This bridge 6 is in the form 50 of a transverse bar supporting a pair of electromagnets 8 which are electrically connected with binding posts 9 on the base 1. 55 A pair of posts 10 and 11 are secured to

the plate 2 and support at their upper ends brackets 12 and 13 respectively which are of general rectangular form. A lever 14 is pivotally supported at one end in the 60 bracket 12 by means of screws 15 and at its other end projects into the bracket 13 and is limited in its vertical movement by the bottom of the bracket and by a set screw 16 in the top of the bracket. An armature 65 17 is secured across the upper face of the lever 14 and has its end portions located above cores 18 of the magnets 8.

A slotted lug 19 projects at right angles to the bracket 12 and receives an angle arm 20, a set screw 21 being provided in the lug 19 to secure the arm 20 at any desired elevation. A rotary device 22, which may constitute an ordinary screw, is positioned horizontally through the slotted free end 23 of 70 the arm 20 and the upper end of a coiled spring 24 is secured to this rotary device 22 and is adapted to be wound thereon to vary the tension of the spring. The lower end of the spring is secured by a screw 25 75 to the center of the armature 17 and to the lever 14.

The bridge 6 is provided centrally with an internally screw threaded collar 26 which receives a vertical screw 27 having 80 rotary mounting in the plate 2 and projecting below the same. A worm wheel 28 is fixed to the lower portion of the screw 27 and is engaged by a worm 29 on a shaft 30, the latter projecting to one side of the base 90 1, supported in suitable bearings 31 and having a knob or finger hold 32 at its outer end to turn the same.

While I have illustrated a receiving instrument, it is obvious that my invention 95 could be applied also to sending instruments.

When desirable, the magnets 8 can be adjusted vertically by means of the shaft 30, worm 29, worm wheel 28, screw 27, and internally screw threaded collar 26 on the bridge 6, the pins 5, 5, operating to hold the bridge in proper transverse position, and the springs 7, 7, affording an elastic support to hold the bridge against wabbling or angular movement. This vertical movement of the magnets 8 operates to vary the gap between the cores 18 of the magnets and the armature 17, so that the desired results can be had in accordance with the 110 current and the general conditions of the apparatus.

The lever 14 with the armature 17 is maintained in elevated position by means of the spring 24 and the tension of the latter can be adjusted by turning the rotary device 22, or by elevating the arm 20, or by both of these means to give the desired resistance to the downward movement of the armature when the magnets are energized, and to cause a quick upward movement 10 when the magnets are deenergized.

Various slight changes might be made in the general form and arrangement of parts described without departing from the invention, and hence I do not limit myself to 15 the precise details set forth, but consider myself at liberty to make such changes and alterations as fairly fall within the spirit and scope of the appended claims.

I claim:

20 1. A telegraph instrument, comprising a base, a bridge above the base, magnets supported on the bridge, an armature above the magnets, means for guiding the vertical movement of the bridge, and means for adjusting the bridge vertically.

25 2. A telegraph instrument, comprising a base, a plate on the base, a bridge above the plate, a vertical screw engaging the bridge and causing the vertical movement of the bridge when said screw is turned, a pair of magnets on the bridge, a movable member, an armature on the movable member above the magnets, a worm wheel on the screw, a shaft projecting laterally from the base, a 30 worm on said shaft, and a finger hold on the outer end of the shaft.

35 3. A telegraph instrument, comprising a base, a plate on the base, a bridge above the

plate, a vertical screw engaging the bridge and causing the vertical movement of the 40 bridge when said screw is turned, a pair of magnets on the bridge, a movable member, an armature on the movable member above the magnets, a pair of upwardly projecting pins guiding the vertical movement of the 45 bridge, springs on the pins between the bridge and the plate, and means for turning the screw to adjust the magnets vertically.

4. A telegraph instrument, comprising a 50 base, a plate above the base, posts on the plate, a lever pivotally connected to one post, means on the other post limiting the pivotal movement of the lever, a bridge above the plate, magnets on the bridge, an 55 armature carried by the lever above the magnets, a lug projecting from one of the posts, an angle arm adjustably secured to said lug, a spring connecting said arm with the lever holding the lever in elevated position, and means for adjusting the magnets vertically.

5. A telegraph instrument, comprising a base, a plate above the base, posts on the plate, a lever pivotally connected to one 65 post, means on the other post limiting the pivotal movement of the lever, a bridge above the plate, magnets on the bridge, an armature carried by the lever above the magnets, a lug projecting from one of the 70 posts, an angle arm adjustably secured to said lug, a spring connecting said arm with the lever holding the lever in elevated position, and means on the arm for adjusting the tension of the spring.

JOSÉ VARGAS GUERRA.
